UNITED STATES PATENT OFFICE.

JOHN WENGS, OF MONROE, MICHIGAN.

MOLD FOR MAKING BUILDING-BLOCKS.

No. 834,954.

Specification of Letters Patent.

Patented Nov. 6, 1906.

Application filed May 18, 1906. Serial No. 317,633.

To all whom it may concern:

Be it known that I, JOHN WENGS, a citizen of the United States of America, residing at Monroe, in the county of Monroe and State of Michigan, have invented certain new and useful Improvements in Molds for Making Building-Blocks, of which the following is a specification, reference being had therein to the accompanying drawings.

10 This invention relates to improvements in molds for forming building or other blocks from cementitious material; and the object of the invention is to provide a mold which is so constructed that the block after being formed therein may be expeditiously removed therefrom without danger of injury to the block and in such a manner as to make it readily accessible for carrying away.

It is also an object of the invention to so 20 make the mold that it may be readily adjusted to increase the length, width, or thickness of the block and so that a carrier-board may be used to form the side or edge of the block and the block released from the mold with 25 either its side or edge downward in the desired position for drying.

To this end the invention consists in mounting the mold to turn bodily upon pivot-bearings, so that after being filled the mold 30 may be swung downward to an inverted position and the block released, and by employing a carrier-board to form one side of the mold the mold may be turned to bring said side downward and the block then released, thus leaving the block in position 35 upon the carrier-board.

The invention further consists in the particular construction, arrangement, and combination of parts, all as hereinafter more fully 40 described, reference being had to the accompanying drawings, in which—

Figure 1 is a front elevation of a device embodying the invention with parts broken away to show the construction; Fig. 2, an end 45 elevation of the same; Fig. 3, a rear elevation, and Fig. 4 a transverse vertical section on the line $\alpha\alpha$ of Fig. 1 and showing the mold-box turned to its inverted position and in dotted lines turned to its horizontal position.

50 As shown in the drawings, a suitable supporting-bench is formed by end frames or legs 1 and a plank 2, forming the top, secured to the upper ends of said frames. Extending laterally from the end frames at their upper 55 ends are brackets forming bearings 3 for a longitudinally-extending shaft 4, provided

with a handle-lever 5 at one end, by means of which the shaft may be easily turned.

6 is the bed-plate of the mold-box and is firmly secured to the shaft 4 by means of 60 bolts 7, sleeves 8 on the bolts being interposed between the shaft and plate to hold the plate at a distance from the shaft, so that it will clear the bearing in turning with the shaft. Ears are provided on the end and 65 rear edges of the bed-plate, and similar ears are provided on the end plates 9 and rear side wall 10 of the mold, forming hinges to connect said end plates and wall to the bed-plate. The front side of the mold-box is formed by 70 bolting two brackets 11 to the bed-plate and placing inside of these brackets a plank or board 12 against the ends of the adjusting-screws 13, which extend through openings in the brackets and are adjustably secured 75 therein by lock-nuts 14, so that the board 12 will be held at the desired distance from the brackets to give the required thickness of cement block.

15 is a movable bottom facing-plate for the 80 mold proper, which bottom is held in place by bolts 16, extending loosely through openings in the bed-plate, so that it may drop a short distance when the mold is inverted and the block released, and 17 represents adjustable end facing-plates for the mold, which are adjustably secured to the end plates 9 by adjusting bolts or screws 18 extending through openings in said ends and adjustably secured therein by lock-nuts 19, the end facing-plates 90 being secured to and supported by the inner ends of said bolts. These end facing-plates may then be easily and accurately adjusted to vary the length of the blocks and move with said ends when the same are turned on 95 their hinges to release the molded block.

A spring 20 is attached at one end to each end plate and at its opposite end to an arm extending outward from the end of the bed-plate and exerts a force to normally turn the 100 end plates outward on their hinges, so that the mold ends will be automatically turned away from the molded block as soon as said ends are released by disengaging the hooks 21, pivotally attached to the rear mold-wall 105 10, from the pins 22, extending outward from the ends of the arms 23 on the end plates, which arms extend longitudinally of the mold from the rear edges of said end plates and are adapted to engage the outer surface 110 of said rear wall when the mold is closed.

The bearings 3 are at one side of the bench-

top 2, and the mold is secured to the shaft 4 at one side of the longitudinal center line of its bed-plate, so that when the mold is in its normal position for filling it is supported by 5 the shaft at one side of its center line and at its opposite edge by the bench-top. The tendency of the mold to turn on its bearings while in this position is thus removed, and the mold is firmly supported without the 10 necessity of securing the same in that position.

After the cement has been thoroughly tamped into the mold a cover to hold it in place while the mold is being turned to the 15 position shown in full lines in Fig. 4 is provided, consisting of a board or plank 24, held in place by bars 25, pivotally attached at one end to the rear wall of the mold and at their opposite ends engaged by hooks 26, 20 pivotally secured to the brackets 11 at the front side of the mold. This board 24 preferably serves as a carrier-board upon which the molded block is removed and set away to dry. To support the board when released 25 from the mold by disengaging the hooks 26 and 21 and turning the mold-wall 10 back, as shown in dotted lines in Fig. 4, any suitable vertically-adjustable support 27 which may be raised into engagement with the board 30 and then lowered to lower the block when the same is released may be employed.

It is often desirable to divide the mold into two parts by a division-wall, as shown by the dotted lines 28 in Fig. 4, and when 35 the wall is placed to divide the mold horizontally the mold is turned to the position shown in dotted lines and the molded blocks released, so that the division-wall may be removed from between the blocks edgewise. 40 The board 12, which forms the front side of the mold, would in this instance serve as the carrier-board for the blocks. With this construction the mold-bottom may be shaped to form a rock-face on that edge of the block as 45 the block is inverted by the turning of the mold and set upon its smooth opposite edge, and a very inexpensive, compact, and easily adjusted and operated device is secured.

Having thus fully described my invention, 50 what I claim is—

1. The combination with a mold-box, of a bench for supporting the mold-box having a top, bearing-brackets on the bench extending laterally therefrom, a shaft rotatable in 55 said bearings at one side of the top, means for securing the mold-box at one side of its longitudinal center line to the shaft to turn therewith, said box being adapted to rest upon said top when in its vertical position 60 and be supported by said top and shaft, and means for turning the shaft.

2. The combination with a mold-box, of a bench having a top, laterally-extending bearing-brackets on said bench, a shaft mounted on said bearing-brackets, bolts secured to 65 the mold-bottom at one side of its longitudinal center line and extending through openings in the shaft, sleeves on the bolts for spacing the mold-box from the shaft, and means for turning the shaft. 70

3. In a mold, the combination with a bed-plate and sides attached to said bed-plate, of end plates hinged to the bed-plate, facing-plates inside the end plates, adjusting-screws extending through the end plates and secured to the facing-plates to adjustably support said facing-plates, and coiled springs attached to the base-plate at one end and to the end plates at their opposite ends to normally hold said ends turned outward on their 80 hinges. 75

4. In a mold, the combination with a bed-plate, of a side and ends hinged to said bed-plate, brackets secured to the bed-plate opposite the hinged side, a detachable board 85 forming the opposite side, adjusting-screws extending through the brackets and engaging the board, a movable bottom facing-plate, arms on the ends adapted to engage the outer surface of the hinged side and provided with outwardly-extending pins, and hooks on the hinged side to engage said pins. 90

5. In a mold, the combination of a bench having laterally-extending bearings, a shaft in said bearings, a bed-plate, bolts extending through said shaft to secure the bed-plate thereto, sleeves on the bolts between the shaft and bed-plate, brackets secured to one edge of the bed-plate, a mold-wall hinged to the opposite edge of said bed-plate, a movable facing-bottom, bolts on the facing-bottom extending through openings in the bed-plate, a board forming the side wall of the mold engaging the brackets, ends hinged to the ends of the bed-plate, facing-plates, adjusting-screws on the ends secured to and supporting said facing-plates, arms on the ends engaging the outer surface of the hinged side wall, pins on said arms, hooks on the side wall engaging said pins, outwardly-extending arms on the ends of the bed-plate, springs attached at one end to said arms and at their opposite ends to the mold ends, a top board, and means for securing the top board in place. 100 105 110 115

In testimony whereof I affix my signature in presence of two witnesses.

JOHN WENGS.
